CLAIM

The ornamental design for a beverage smoker device as shown and described.

DESCRIPTION

FIG. 1 is a perspective view of the beverage smoker device; FIG. 2 is a front elevational view of the beverage smoker device;

FIG. 3 is a back elevational view of the beverage smoker device;

FIG. 4 is a right side elevational view of the beverage smoker device;

FIG. 5 is a left side elevational view of the beverage smoker device;

FIG. 6 is a top plan view of the beverage smoker device;

FIG. 7 is a bottom plan view of the beverage smoker device;

FIG. 8 is a cross-section view of the beverage smoker device taken in the direction of line 8-8 of FIG. 6;

FIG. 9 is an exploded top perspective view of the beverage smoker device;

FIG. 10 is an exploded bottom perspective view of the beverage smoker device; and,

FIG. 11 is a bottom plan view of the top portion of the beverage smoker device.

The broken lines showing a beverage container in FIGS. 9 and 10 represent environment and form no part of the claimed design. All other broken lines represent portions of the beverage smoker device and form no part of the claimed design.

1 Claim, 11 Drawing Sheets
